(57) **CLAIM**

The ornamental design for a pipette stand, as shown and described.

DESCRIPTION

FIG. 1 is a front, top, and left perspective view of a pipette stand according to the invention.

FIG. 2 is a rear, bottom, and right perspective view of the pipette stand.

FIG. 3 is a front view of the pipette stand.

FIG. 4 is a left side view of the pipette stand.

FIG. 5 is a rear view of the pipette stand.

FIG. 6 is a right side view of the pipette stand.

FIG. 7 is a top view of the pipette stand; and,

FIG. 8 is a bottom view of the pipette stand.

The broken lines in the drawings depict portions of the pipette stand that form no part of the claimed design.
